Debrandt, Mr. Dowell & Co.
Designers of
James Horton.
Design for a coal stove.

Des. 739

James Horton, of Philadelphia, Pa.

Assignor to.

Leibrandt, McDowell & Co. of Philadelphia, aforesaid.

Letters Patent No. 739, dated Oct. 30, 1855

The schedule referred to in these Letters Patent, & making part of the same.

To all whom it may concern,

Be it known that I, James Horton, of the City and County of Philadelphia, & State of Pennsylvania, have invented a new & original design for a Coal-Stove, which I call the "Magnolia", and that the following is a full, clear, & exact description of the same, reference being had to the accompanying drawings, making a part thereof, in which

Fig 1. represents a perspective view of the front, & one of the sides, and

Fig 2. represents a rear elevation of the stove.

To enable others skilled in the art, to make & use my invention, I will proceed to describe the same, with reference to the drawings. —

A, represents the bottom plate, having a moulding a, wrought around its edge, & supported upon the legs B. The bottom plate projects in front sufficiently far to form the hearth.

The centre piece C, of the front plate is a magnolia, surrounded by a foliated vine b, and forming near by a square panel. Above this panel is the door D, in another panel, & cast in volutes e. in open work. The two panels are surrounded by light beadings d, & between the beadings are alternate oval & diamond shaped ornaments e. f, with scroll work at the angles, margining the whole of the ornamental work, except that on the register plate E, which beside its openings g, has a quatre-foil h, at each side for ornament.

The pilasters at the corners, & moulding at the top & bottom of the side plates, are Gothic.

The side plate F, (both side plates being alike) is embellished with foliated volutes, embracing at the bottom an armorial shield G, & at top, a magnolia H, surmounted by a shell escutcheon I.

The back plate (fig 2) is ornamented with scroll work, & foliated volutes, bound & intertwined together, to form a pyramid of ornament, as seen in the drawing. J, represents the flange for the pipe.

The top plate K, is highly raised from the sides, and with its mouldings i, and ornaments j, forms a plain panel on its top, in the centre of which, stands a vase cover L, in open work, which gives a finish to the design. The ornaments are in alto, the mouldings in alto. & bapo-relievo

Having thus fully described the nature of my design, what I claim therein as new, & desire to secure by letters patent, is the combination of ornaments herein described, the whole forming an original design for a Coal Stove.
